UNITED STATES PATENT OFFICE.

MICHAL KOLTONSKI, OF CHICAGO, ILLINOIS.

FOLDING BOX.

1,113,654.

Specification of Letters Patent.

Patented Oct. 13, 1914.

Application filed September 30, 1913. Serial No. 792,641.

To all whom it may concern:

Be it known that I, MICHAL KOLTONSKI, a subject of the Emperor of Russia, residing at Chicago, in the county of Cook and State 5 of Illinois, have invented certain new and useful Improvements in Folding Boxes, of which the following is a specification, reference being had therein to the accompanying drawing.

10 This invention relates to folding boxes, and more particularly to a box or crate that can be advantageously used for shipping eggs and other matter that require separate compartments.

15 The primary object of my invention is to provide a collapsible or foldable box having novel collapsible partitions that permit of the box being folded to occupy a comparatively small space in storage or during 20 return shipment.

Another object of this invention is to provide a strong and durable folding box consisting of comparatively few parts that present a rigid structure when set up.

25 A further object of this invention is to provide a simple and inexpensive folding egg box that has novel hinges that permit of the box being compactly held when knocked down.

30 With the above and other objects in view the invention resides in the novel construction, combination and arrangement of parts to be hereinafter specifically described and then claimed.

35 Reference will now be had to the drawings, wherein:

Figure 1 is a plan of the box, Fig. 2 is a longitudinal sectional view of the same in a set-up position, Fig. 3 is a similar view of 40 the box in a folded position, Fig. 4 is a cross sectional view of the box in a set up position, Fig. 5 is a similar view of the box in a folded position, and Fig. 6 is an enlarged perspective view of portions of partitions 45 used in connection with the box.

A folding box in accordance with this invention comprises a rectangular base plate 1 that has the edges thereof provided with permanent end walls 2 and permanent front 50 and rear walls 3 and 4. The end walls 2 are of a greater height than the walls 3 and 4 and said walls are braced relatively to the bottom plate 1 by corner pieces 5.

Hinged, as at 6 to the permanent front 55 wall 3 is a foldable front wall 7 having the outer side thereof provided with a staple 8,

the permanent front wall also has a staple 8a. Hinged to the rear wall 4, as at 9 is a foldable rear wall 10 and the walls 7 and 10 are adapted to fold inwardly upon a horizontal plane. The hinged rear wall 10 has openings 11 and countersunk in the outer side of said wall, at said openings are plates 12 that are slotted, as at 13 to provide hinge rods or pivots 14. Hinged to the end walls 2, as at 15 are foldable end walls 16 and these walls are adapted to fold inwardly upon the hinged front and rear walls 7 and 10.

The reference numeral 17 denotes a lid 70 that is provided with angle corner pieces 18 and these pieces fit downwardly over the upper edges of the walls 7, 10 and 16, to brace said walls when in a set up position. The front edge of the lid 17 has a hinged 75 hasp 19 to engage over the staple 8. The rear edge of the lid 17 has angle straps 20 terminating in hooks 21 adapted to engage the rods or pivots 14, as best shown in Fig. 4.

The permanent rear wall 4 has plates 22 and rods or pivots 23 to receive the hooks 21 when the box is folded and in order that the lid can be used, as shown in Fig. 5 it is necessary that said lid have an opening 24 85 to provide clearance for the staple 8 of the hinged front wall 7.

The reference numerals 25 denote a plurality of horizontal partitions and hinged to said partitions, as at 26 are longitudinal 90 equally spaced partitions 27 provided with equally spaced slots 28 to receive equally spaced transverse partitions 29. The partitions 29 are slotted, as at 30 whereby the partitions 27 and 29 can be fitted together 95 to provide a plurality of compartments. The partitions can be easily collapsed and placed one upon the other as shown in Figs. 3 and 5 whereby when the box is folded it will present a rigid and durable structure. 100

The box can be made of wood and the trimmings of metal, or any other suitable material can be used throughout the construction of the box.

One embodiment of the invention has 105 been illustrated, but it is to be understood that the structural elements are susceptible to such variations and modifications as fall within the scope of the appended claim.

What I claim is:

110 A folding box comprising a bottom having permanent end, front and rear walls secured

thereto, pivot plates disposed on said permanent rear wall, foldable front and rear walls hinged to the upper edges of said permanent front and rear walls, foldable end walls hinged to the upper edges of said permanent end walls, pivot plates carried by said foldable rear wall, a lid, a hasp disposed on the edge of said lid, and straps carried by the rear edge thereof and provided with hooks 10 adapted for engagement with the pivot plates of said foldable and permanent rear walls, staples disposed on said foldable and

permanent front walls adapted to receive said hasp, corner pieces secured to said lid, horizontal partitions having hinged longitudinal partitions secured thereto and detachable transverse partitions adapted to interlock the said hinged partitions. 15

In testimony whereof I affix my signature in the presence of two witnesses.

MICHAL KOLTONSKI.

Witnesses:

STEFEN LUHAREWSKSI,
MATT WILKANS.
